UNITED STATES PATENT OFFICE.

MICHAEL J. PINKLO, OF WEST NEW YORK, NEW JERSEY, ASSIGNOR OF ONE-FOURTH TO BERNHARD PROCHNOW AND ONE-FOURTH TO BERNHARD PROCHNOW, JR., BOTH OF GUTTENBERG, NEW JERSEY.

CONNECTION FOR BEDSTEADS AND THE LIKE.

Application filed August 4, 1923. Serial No. 655,563.

To all whom it may concern:

Be it known that I, MICHAEL J. PINKLO, a citizen of the United States, and a resident of West New York, in the county of Hudson and State of New Jersey, have invented certain new and useful Improvements in Connections for Bedsteads and the like, of which the following is a specification.

10 This invention relates more especially to the connection of the ends of the side rails of a metal bedstead with the corner posts of the head and foot, although it will be understood that it can be used for connecting 15 similar members in other constructions than bedsteads, and I contemplate use of the connection wherever it is applicable.

The objects of the invention are to secure 20 a detachable connection of the side rails of the bedstead to the corner posts of the foot and head which shall be readily detachable and yet firm and secure; to obtain a simple and easily operated construction which shall be strong and not liable to breakage; 25 to enable the side rails to be reversed and used either side up, as in the case of angle iron; to provide a construction which will automatically lock when put together, and yet is easily detached or taken apart, and to 30 obtain other advantages and results as may be brought out by the following description.

Referring to the accompanying drawing, in which like numerals of reference indicate the same parts throughout the several views.

35 Figure 1 is a side view of a portion of a bed post and side rail having my improved connection, shown partly in section on line 1-1 of Fig. 3;

Figure 2 is a section on line 2-2 of 40 Fig. 1;

Figure 3 is a plan of the connection as shown in Figures 1 and 2;

Figure 4 is a side elevation corresponding to Figure 1, the side rail being about to be 45 connected;

Figure 5 is a side elevation corresponding to Figures 1 and 4 with the side rail in place;

Figure 6 is a perspective view of the connecting end of a rail, and

Figure 7 is a vertical sectional view illustrating a modified form of the connection in

which upper and lower sliding pins engage the end piece.

In the specific embodiment of the invention 55 shown in Figures 1 to 6, inclusive, 1 indicates one of the posts of either the head board or foot board of a metal bedstead, and 2 indicates one of the side rails. The post 1 is shown hollow and round and the rail 2 is 60 shown of angle iron, although both or either of these parts might be of any other common and known form.

To the outside of the post 1 is suitably secured, as by spot welding at 3, 3, a bracket 4 65 which is in general channel-shaped with a connecting portion or back 5 lying against the post 1 and wings 6, 6 projecting therefrom. One of the wings has a laterally projecting lug 7 to which is bolted a bar 8 which 70 extends to a similar lug on the similar bracket of the opposite post (not shown) of the head board or foot board.

The wings 6, 6 of the bracket 4 have opposite slots 9 which are inclined downwardly 75 toward the post 1 and are preferably slightly curved convexly toward the post, as shown. In these slots 9 slides a pin 10 having at one end a head 11 outside the bracket and at the other end a washer 12 and cotter pin 13 also 80 outside the bracket. The pin also preferably carries a tubular friction roller 14 between the wings 6, 6 of the bracket 7. The side rail 2 is provided at its end with an end piece 15, the stem 16 of which is shown made fast to the 85 side rail, as by means of rivets 17, 17 extending through one of the flanges of the angle iron side piece. The outer end of the end piece is provided with a right angular arm 18, which is preferably curved at its junction 90 with the stem 16 to seat the sliding pin on its roller 14, said arm being also of a thickness such that it will jam between the closed portion 5 of the bracket and the said pin 10 or roller 14 as the latter moves downward in 95 the inclined slots 9. Obviously, by hooking the arm 18 over the sliding pin while it is at an upper portion, as shown in Figure 4, and then pressing down, the parts will assume the position shown in Figures 1 and 5 and a 100 firm, tight connection will be made. At the same time, disconnection is readily effected by moving the end of the side rail 2 upward, with the sliding pin 10.

The inner engaging side of the arm 18 is preferably hollowed or recessed as at 19 so as to more positively hook onto the sliding pin, and furthermore, this enables the end 5 piece to be hooked on from either above or below the sliding pin. The side rail can therefore be reversed, or turned upside down, as shown in dotted lines in Figure 1, a little more care being exercised in holding 10 the arm of the end piece in place behind the sliding pin until the parts are firmly wedged in position. Such reversal is useful in adapting a bedstead with angle iron side rails to be used either with or without slats. 15 Preferably, the end piece 15 is provided with an arm 20 opposite the arm 18, so that the side rail can be reversed if desired, according to whether or not slats are used in the bedstead or for any other purpose. 20 Furthermore, the opposite arm 20 gives a firmer bearing of the end piece against the closed portion 5 of the bracket, as shown in Figure 1.

In Figure 7 I have shown a bracket 21 provided with two pairs of straight inclined slots 22, 22, a pin 23 being mounted in each slot, so that when the T-headed end piece 24 is inserted it will be engaged by a sliding pin both above and below itself. This construction may be used if greater security is desired. 30

Also in Figure 7 I have shown the bracket 21 secured to the post 25 by bolts 26 extending through the wall of the hollow 35 post and screwing into a retaining piece 27 against the inner side of said wall.

Obviously, the bracket and end piece of my improved connection could be applied to wooden bed posts and side rails if desired, 40 and as I stated in the beginning of this specification could be applied to any other structures than bedsteads, without departing from the spirit and scope of the invention; therefore, I do not wish to be understood as limiting myself except as required by the following claims when construed in the light of the prior art.

Having thus described the invention, what I claim is:

50 1. The combination with a bracket adapted to be applied to a post and providing a projecting wing with a slot inclined downwardly toward said post, and a sliding pin in said slot, of an end piece on a

rail or the like having a lateral arm to hook 55 onto said sliding pin and be jammed thereby toward the post by downward movement.

2. The combination with a bracket adapted to be applied to a post and providing a projecting wing with a curved slot inclined downwardly and convexly toward 60 said post, and a sliding pin in said slot, of an end piece on a rail or the like having a lateral arm to hook onto said sliding pin and be jammed thereby toward the post by downward movement. 65

3. The combination with a bracket adapted to be applied to a post and providing a projecting wing with a slot inclined 70 downwardly toward said post, and a sliding pin in said slot, of an end piece on a rail or the like having a T-head to hook onto said sliding pin and be jammed thereby toward the post by downward movement. 75

4. The combination with a bracket 80 adapted to be applied to a post and providing a projecting wing with parallel slots inclined downwardly toward said post, and sliding pins one in each of said slots, of an end piece on a rail or the like having a T-head to hook between said sliding pins and be jammed thereby toward the post by downward movement. 85

5. The combination with a bracket 90 adapted to be applied to a post and providing opposite wings with parallel pairs of slots inclined downwardly toward said post, and sliding pins one in each of said pairs of slots, of an end piece on a rail or the like having a T-head to hook between said sliding pins and be jammed thereby toward the post by downward movement. 95

6. The combination with a post having a bracket and a transverse member on said bracket movable wedgingly toward the post, 100 of an end piece on a rail or the like having a lateral arm to extend between said post and member and be jammed by the latter toward the post upon downward movement. 105

7. The combination with a bracket 100 adapted to be applied to a post and providing a projecting wing, and a transverse member on said wing movable wedgingly with respect to the post, of an end piece on a rail or the like having a lateral arm to hook onto 105 said member and be jammed thereby toward the post by downward movement.

MICHAEL J. PINKLO.
